US0D1029866S

(12) **United States Design Patent** (10) **Patent No.:** **US D1,029,866 S**
(45) **Date of Patent:** **** Jun. 4, 2024**

(54) **DISPLAY SCREEN OR PORTION THEREOF WITH GRAPHICAL USER INTERFACE**

(71) Applicant: **Salesforce, Inc.**, San Francisco, CA (US)

(72) Inventors: **Andrew Mangano**, Sunnyvale, CA (US); **Stephen Goldberg**, Frisco, TX (US); **Saurabh Davala**, San Francisco, CA (US); **Umesh Zope**, Fremont, CA (US); **Saket Agarwal**, San Mateo, CA (US); **Abigail Sigler**, San Francisco, CA (US)

(73) Assignee: **Salesforce, Inc.**, San Francisco, CA (US)

(**) Term: **15 Years**

(21) Appl. No.: **29/864,391**

(22) Filed: **May 25, 2022**

(51) **LOC (14) Cl.** **14-04**

(52) **U.S. Cl.**

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
